[57] CLAIM

The ornamental design of a receptacle, as shown and described.

DESCRIPTION

FIG. 1 is a perspective oblique view from above of the receptacle in its closed state;

FIG. 2 is a perspective oblique view from above of the receptacle in its partly opened state;

FIG. 3 is a perspective oblique view from above of the receptacle in an entirely unfolded state, the inner side of said receptacle forming a support surface;

FIG. 4 is a perspective oblique view from above of the receptacle in a partly closed state, with holding straps being disposed inside the receptacle which could serve to hold utensils therein;

FIG. 5 is a side view of the receptacle in its closed state;

FIG. 6 is a top view of the receptacle in its closed state;

and,

FIG. 7 is a bottom view of the receptacle in its closed state.
